UNITED STATES PATENT OFFICE.

WILLIAM C. NICOL, OF EVERETT, WASHINGTON, ASSIGNOR OF ONE-HALF TO ALEXANDER G. PASCHKE, OF EVERETT, WASHINGTON.

TRIP HAMMER.

Application filed October 2, 1923. Serial No. 666,147.

To all whom it may concern:

Be it known that I, WILLIAM C. NICOL, a citizen of the United States, residing at Everett, in the county of Snohomish and State of Washington, have invented certain new and useful Improvements in a Trip Hammer, of which the following is a specification.

This invention appertains to power machinery and more particularly to trip hammers used for forging or like purposes where quick even blows are essential and the primary object of the invention is the provision of an automatically operated trip hammer embodying novel means for quickly setting the trip hammer in operation and for bringing about the effective and instant stopping thereof.

A further prime object of the invention is the provision of a trip hammer embodying a drive shaft, operatively connected to the hammer through the medium of a crank and pitman and novel means for bringing the drive shaft into operation and means for bringing a brake band from out of engagement with the shaft, said means also permitting the releasing of the drive shaft and the setting of the brake, when it is desired to bring about the instant stopping of the hammer.

A further object of the invention is the provision of novel means for resiliently connecting the crank with the hammer, thereby giving an elastic movement to the hammer, the throw of the crank and the give of the spring transmitting to the hammer a quick and powerful movement.

A still further object of the invention is to provide a trip hammer of the above character, which will be durable and efficient in use, one that will be simple and easy to manufacture, and one which can be placed upon the market at a small cost.

With these and other objects in view, the invention consists in the novel construction, arrangement and formation of parts, as will be hereinafter more specifically described, claimed and illustrated in the accompanying drawings, in which drawings:

Figure 1 is a front elevation of the improved trip hammer.

Figure 2 is a side elevation of the same.

Figure 3 is a detail section taken on the line 3—3 of Figure 1 and

Figure 4 is a detail horizontal section 55 taken on the line 4—4 of Figure 1.

Referring to the drawings in detail, wherein similar reference characters designate corresponding parts throughout the several views, the letter A generally indicates the improved hammer, which comprises the supporting post or standard 5, which can be formed of any desired material, such as wood or iron. The upper end of the post 5 has bolted or otherwise secured thereto at one side face thereof the upstanding supplemental supporting post 6. Directly below the supplemental supporting post 6 and in spaced relation thereto is arranged a supporting bed 7, which is also bolted to one side face of the main supporting post or standard 5. This bed 7 has secured thereto the anvil supporting standard 8, to which is affixed the anvil 9, which can be of any preferred type. The front face of the supporting post 5 can carry any preferred type of bracket 10 for receiving different kinds of swedges, so that the swedges can be moved into engagement with the active face of the anvil 9.

The lower end of the supplemental support or post 6 carries the guide 11 for the hammer proper 12, which includes the thin shank 13 reciprocably mounted in the guide 11 and the hammer head 14, which is disposed directly above the anvil 9.

The guide 11 includes pairs of spaced guide plates 15 and the plates of each pair of guide plates are held in spaced relation, by spacing plates 16. These spacing plates 16 are adjustable toward the hammer shank 13 in order to take care of wear and to prevent any slip between the guide and hammer. The adjusting means includes a horizontal bolt 14' having nuts 15' threaded on its terminals for engaging the follower plates 16', which bear against the outer ends of the spacing plates 16. The guide 11 can be bolted to a suitable supporting face plate 17, carried by the supplemental supporting post 6, so as to permit the guide 11 to be held away from the face of the supporting

post. The extreme upper end of the supplemental supporting post 6 can be bolted or otherwise secured to a suitable ceiling joist 18 or the like and the upper end of this post carries a rotatable drive shaft 19, one end of which has secured thereto the operating crank 20 and the other end a brake drum 21, which receives the brake band 22. The drive shaft 19 has also keyed thereto adjacent to the crank 20 a drive pulley 23 around which is trained a drive pulley belt 24, that can lead from any suitable source of power, such as a motor, or line shaft. The drive shaft 19 can be supported by any preferred type of bearings 25 carried by the post 6.

The crank 20 carries a depending pitman rod 26, which is in turn connected by means of a clevis 27 or the like to the central portion of a semi-elliptical leaf spring 28, the terminals of which carry links 29. The links 29 are fixed to their opposite sides of the shank 13 of the hammer 12 proper.

It is obvious that when the crank 19 is operated by the belt 24, the hammer proper 12 will be quickly raised and lowered and owing to the links 29 and the spring 28, a quick and effective blow will be delivered to the anvil at each throw of the crank arm. The belt 24 is a loose belt and normally the same will not rotate the pulley 23 and in order to bring about the drive of the pulley 23 from the belt 24, the said belt must be tightened.

In order to bring about the tightening of the belt, I provide a swinging frame 30 rotatably mounted upon one side face of the supplemental supporting post or beam 6, as at 31. The upper end of the swinging frame 30 carries an idler pulley 32 for engaging the belt 24. A rearwardly extending operating arm or lever 33 is rigidly formed on the frame 30 at a point spaced from its pivot 31 and this arm or lever 33 has secured thereto an operating or pull chain 34, which extends down toward the base of the trip hammer. This chain 34 is inserted through a suitable ring 35 carried by the treadle 36 and the lower end of the chain 35 is rigidly bolted or otherwise secured to the standard 5, as at 36. It is obvious that when the treadle 36 is thrown downward by the foot, that the lever 33 will be moved downward, thus bringing the idler pulley 32 into forcible contact with the belt 24, thus bringing about the tightening thereof, and the consequent rotation of the shaft 19. When the foot pedal 36 is released, the same will be moved to a raised position by the use of a contractile coil spring 37 secured at one end to the treadle and to the opposite end to the bed 7, as at 38. The lever 33 will also be returned to its normal position upon the release of the pedal 36 by means of a contractile coil

spring 39, the lower end of which is connected to the lever and the opposite end to the ceiling joist 18.

In order to bring about the quick and positive stopping of the trip hammer 14 when the treadle 36 is released, I connect the brake band 22 to the swinging frame 30 by means of a rod 40 and it is obvious, that upon release of the frame, the same will swing away from the post 6 and thus exerting a pull on the brake band 22 which will act upon the brake band 21 and stop the operation of the shaft.

When the frame 30 is operated by the treadle for tightening the belt 24, it can be seen that the frame 30 will move inwardly toward the post 6, thus loosening the brake band 22 and permitting the rotation of the shaft 19.

The treadle 36 can be of any desired construction, and as shown the same consists of a pair of parallel arms 42 and a transverse foot bar 43. The arms 42 being pivoted as at 43 to any preferred type of support.

From the foregoing description, it can be seen that I have provided an exceptionally simple and durable power trip hammer, which will effectively accomplish the purpose intended. The trip hammer is also formed with a purpose in view, to allow the same to occupy a minimum amount of space in a shop and it can be seen that the same will only take up an area of a shop equal to the area of the lower face of the supporting posts 6 and 7 and the iron block 8.

Changes in details may be made without departing from the spirit or the scope of this invention.

What I claim as new is:

1. A power trip hammer comprising a supporting post, an anvil block, an anvil secured to the block, a supplemental supporting post secured to one side face of the main supporting post, a guide carried by the supplemental supporting post, a reciprocatory hammer head mounted in said guide, bearings carried by the supporting post, a rotatable drive shaft mounted in the bearings, and a crank carried by one end of the drive shaft, a pitman connected with the crank, a semi-elliptical leaf spring secured to the pitman rod, links connecting the terminals of the leaf spring with the upper end of the hammer head, a drive pulley secured to the drive shaft, a brake drum secured to the drive shaft, a brake band for the drum, a frame pivotally connected with the supplemental post, an idler pulley connected with the frame for engaging the drive belt, means connecting the brake band with the swinging frame, an operating lever secured to the frame at one side of the pivot, means for normally holding the frame away from said post and the idler pulley out of operative contact with the

drive pulley belt and the brake band in operative braking engagement with the brake drum, a foot treadle carried by the lower end of the supporting post, means operatively connecting the lever with the foot treadle, and means for normally holding the foot treadle in a raised position.

2. In a power trip hammer, a supporting post, an anvil block carried by the post, an anvil secured to the block, a guide associated with the post including a pair of spaced plates disposed on each side of the longitudinal center of the post, a reciprocating hammer including a relatively thin flat shank slidably mounted between the

plates of the pair of plates, a crank shaft, means operatively connecting the crank shaft with the shank of the hammer, spacing plates disposed between the plates of the pair of plates, and means for adjusting 30 said spacing plates toward and away from the shank of the hammer, as and for the purpose specified.

In testimony whereof I affix my signature in presence of two witnesses.

WILLIAM C. NICOL.
